INVENTOR

BY *Victor J. Evans*

ATTORNEY

UNITED STATES PATENT OFFICE.

RALPH CAVERLY, OF CHICAGO, ILLINOIS.

DRILL BIT.

1,427,064.

Specification of Letters Patent. Patented Aug. 22, 1922.

Application filed November 6, 1920. Serial No. 422,288.

To all whom it may concern:

Be it known that I, RALPH CAVERLY, a citizen of the United States, residing at Chicago, in the county of Cook and State of Illinois, have invented new and useful Improvements in Drill Bits, of which the following is a specification.

This invention relates to rotary drill bits of the type used in deep well drilling, and 10 an object of the invention is to provide a positive acting rotary drill bit comprising a plurality of cutters which normally rest out of cutting position and are forced into cutting position at predetermined intervals by 15 suitable gearing, to effectively drill a well of uniform diameter with minimum effort.

A further object of the invention is to provide a drill bit as specified, in which the cutters are shaped to guide the cuttings inwardly to suitable suction pipes thereby preventing clogging of the drill due to accumulation of cuttings.

Other objects of the invention will appear in the following description taken in connection with the accompanying drawing wherein:

Fig. 1 is a longitudinal section through a drill showing the improved bit applied.

Fig. 2 is a bottom plan of the improved 30 bit.

Fig. 3 is a horizontal section through the bit taken on line 3—3 of Fig. 1.

Fig. 4 is a detailed vertical section through the port of the bit structure.

The improved drill bit is of the rotary type, including a drive shaft 1 which is rotatably supported in suitable bearing members 2 and 3. The bearing members 2 and 3 are rigidly mounted in a suitable casing 4 of 40 the drill structure as disclosed in my companion application filed November 6, 1920—Serial No. 422,289. A stuffing box 5 is mounted in the bearing member 2 to form a fluid tight joint about the rotary drive shaft 1 to 45 prevent seeping of water or other liquid into the casing 4. The upper end of the shaft 1 has a gear 6 rigidly mounted thereon which is connected, by a suitable gear train 7 to a prime mover 8 of any conventional form. 50 The gearing 7 is adapted to reduce the speed of rotation and consequently increase the power applied to the shaft 1 through the gear 6.

A spider 9 is rigidly mounted upon the 55 lower end of the shaft 1 and comprises a plurality of radiating arms 10, each of which

is recessed vertically, as at 11. The recesses 11 receive therein shafts 12, which are enlarged at their lower ends as shown at 13 and have the cutting bits 14 formed integral therewith. As clearly shown in Fig. 4 of the drawing, the recesses 11 are longer than the enlarged portions 13 of the shafts 12 and spiral springs 15 are mounted therein, being coiled about the shafts 12 and having ends 65 engaging in suitable recesses 16 formed in the arms 10 while their other ends engage in recesses 17 formed in the enlarged portions 13. Each of the shafts 12 has a pinion 18 rigidly mounted thereon, and meshing with 70 a gear 19 rotatably mounted upon the drive shaft 1. Nuts 20 are mounted on the shafts 12 to prevent vertical movement of these shafts relative to the spider 9. The cutters 14 have their outer ends curved as shown at 75 21, their concave sides 22 form cutting edges and terminate in relatively sharp cutting edges 23 which, when the cutters are in operative cutting position project beyond the edge of the well case 24 and drill a hole 80 slightly larger than the case 24 to permit the latter to move freely into a well being drilled. The cutters rotate in the direction indicated by the arrow A, and thus the cuttings made by the cutters will travel over 85 the concave sides 22, inwardly towards the axis of the shaft 1, and they will be taken up by the suction pipes 25, which are more specifically described in my companion application heretofore referred to.

The cutters 21 have heels 26 formed thereon which extend inwardly towards the shaft 1 and are adapted to engage against the shaft to limit the relative rotation of the cutters 21 and maintain them in the proper 95 cutting position. These heel projections 26 have their upper surfaces recessed as at 27 to permit the passage of the cutting ends of the cutters thereover, when the cutters are folded inwardly out of cutting position as 100 indicated by the cutter 14 at the upper left hand side of Fig. 2 of the drawing.

The lower end of the drive shaft 1 is pointed as indicated at 28 to permit its free rotation in the bottom of the well being 105 drilled.

The gear 19 being loosely mounted upon the shaft 1 together with the pinions 18 causes all the cutters to move outwardly in cutting position, or inwardly out of cutting 110 position simultaneously. The cutters 14 are moved inwardly out of cutting operation

when the drill structure is lifted by the spiral springs 15.

It is, of course, to be understood that the invention may be constructed in various 5 other manners and the parts associated in different relations and, therefore, I do not desire to be limited in any manner except as set forth in the claims hereunto appended.

Having thus described my invention what 10 I claim is:

1. In a drill bit, a supporting spider, a plurality of cutters pivotally carried by said spider, means connecting said cutters to cause simultaneous movement of the cutters, 15 and a drive shaft connected to said supporting spider.

2. In a drill bit, a drive shaft, a spider rigidly mounted on said drive shaft, a plurality of cutters pivotally carried by said spider, means connecting said cutters for simultaneous movement into or out of cutting positions, and means for automatically removing said cutters out of cutting positions at predetermined times. 20

3. In a drill bit, a drive shaft, a spider rigidly mounted on said drive shaft, a plurality of cutters carried by said spider for pivotal movement relative thereto, heel projections formed upon said cutters and 25 adapted to engage said drive shaft for limiting movement of the cutters relative to the spider.

4. In a drill bit, a drive shaft, a spider rigidly mounted on said drive shaft, a plurality of cutters carried by said spider for pivotal movement relative thereto, heel projections formed upon said cutters and 30 adapted to engage said drive shaft for limiting movement of the cutters relative to the spider.

40 spider, said cutters provided with concave edges for guiding the cuttings inwardly towards the axis of said drive shaft.

5. In a drill bit, a drive shaft, a spider rigidly mounted on said drive shaft, a plurality of cutters carried by said spider for 45 pivotal movement relative thereto, heel projections formed upon said cutters and adapted to engage said drive shaft for limiting movement of the cutters relative to the spider, said cutters provided with concave 50 edges for guiding the cuttings inwardly towards the axis of said drive shaft, and gears connecting said cutters for simultaneous movement into and from cutting positions.

6. In a drill bit, a drive shaft, a spider 55 thereon, a plurality of cutters pivotally carried by said spider, means connecting said cutters to cause simultaneous movement of the cutters, and means for limiting movement of the cutters relative to said spider. 60

7. In a drill bit, a drive shaft, a spider thereon, a plurality of cutters pivotally carried by said spider, means connecting said cutters to cause simultaneous movement of the cutters into and out of cutting positions, 65 means for automatically moving said cutters out of cutting positions at predetermined times, and means formed on said cutters for limiting movement of the cutters relative to said spider. 70

8. In a drill bit, a drive shaft, a spider thereon, a plurality of cutters pivotally carried by said spider, means connecting said cutters for simultaneous movement into or out of cutting positions, means for automatically moving said cutters out of cutting positions at predetermined times, and heel 75 projections formed on said cutters for engagement with said drive shaft for limiting movement of the cutters relative to the spider. 80

In testimony whereof I affix my signature.

RALPH CAVERLY.
